DESIGN FOR A MUFF

Max Baer, New York, N. Y.

Application April 8, 1942, Serial No. 106,489

Term of patent 3½ years

To all whom it may concern:

Be it known that I, Max Baer, a citizen of the United States, residing in New York city, in the county of New York and State of New York, have invented a new, original, and ornamental Design for a Muff, of which the following is a specification, reference being had to the accompanying drawing, forming part thereof.

Fig. 1 is a front view of a muff showing my new design, and

Fig. 2 is a side view of the muff shown in Fig. 1, and

Fig. 3 is a rear view of the muff shown in Fig. 1.

I claim:

The ornamental design for a muff, substantially as shown.

MAX BAER.
